UNITED STATES PATENT OFFICE.

ROBERT N. CORTHELL, OF AUBURN, MAINE, ASSIGNOR TO SUMMIT THREAD COMPANY, OF EAST HAMPTON, CONNECTICUT, A CORPORATION OF MAINE.

GUARDING ATTACHMENT FOR THREAD COPS.

Application filed April 5, 1926. Serial No. 99,933.

This application is a continuation in part of my application filed November 16, 1925, Serial No. 69,303.

The invention relates to a thread cop 5 which includes a tubular core, and a thread body wound thereon and composed of universally wound layers, the cop being adapted to be supported by a stand which includes a base and a spindle extending into 10 the core, the stand permitting the rotation of the cop by the pull of the thread unwound therefrom.

It is customary to provide at the inner end of the cop, a guard interposed between said 15 end and the stand base, and adapted to prevent the catching of the thread being unwound from the cop between the inner end of the latter and the stand base.

The object of the invention is to provide 20 an improved attachment of simple and inexpensive construction, adapted to be separably engaged with the inner end portion of the core, and provide a guard adapted to prevent the catching of thread between the 25 stand base and the inner end of the cop.

Of the accompanying drawings forming a part of this specification,—

Figure 1 is an enlarged plan view of a 30 guarding attachment embodying the invention, separated from the cop, portions being broken away.

Figure 2 is a sectional view on line 2—2 of Figure 1.

Figure 3 is a view similar to Figure 2, 35 showing a modification, an end portion of the cop being shown in section.

Figure 4 is a perspective view, showing one member of the two-part base portion hereinafter described.

Figure 5 is a plan view, showing the blank 40 from which the member shown by Figure 4 may be made.

Figure 5^a is a modification of Figure 5.

Figure 6 is a perspective view of a differently constructed guarding attachment embodying the invention.

Figure 7 is a section on line 7—7 of Figure 6.

Figure 8 shows in section an end portion 50 of a cop, and a guarding attachment constituting another embodiment of the invention, engaged with a cop.

Figure 9 shows in perspective the split ring shown by Figure 8.

Figures 1 to 4 show the device enlarged 55 from the usual size, which is indicated by Figures 6, 7 and 8.

The same reference characters indicate the same parts in all of the figures.

A thread cop with which my attachment 60 is used includes a tubular core *a* usually of paper, and open from end to end, and a thread winding or body *b* usually composed of universally wound layers, the body being cylindrical and having substantially flat 65 ends. When in use the cop is supported by a stand including a base and a spindle, the latter extending from the base into the core.

Each of the hereinafter described embodiments of my invention comprises an annular head, formed to bear on an end of the cop and provided with a central opening to receive the spindle, and a clutch including a series of flexible tongues supported by the 75 head, projecting upward from the margin of the head opening and adapted to enter the core *a*, and a normally expanded split ring engaged with the tongues and adapted to enter the core, the ring being contracted 80 from its normal diameter, when inserted in the core, so that its effort to expand causes the clutch to frictionally engage the internal surface of the core, maintain the head in contact with the cop, and permit the removal 85 of the attachment from the cop for use with another cop.

In the embodiment of the invention shown by Figures 1 and 2, the head includes an annular facing portion 12, of compressible 90 material, such as sheet felting contacting with the cop, and a two-part base portion including an annular member 13 of sheet metal, and an annular member 13^a of non-metallic material, such as fiberboard, which 95 is stiffer than the facing portion 12, supports all parts of the facing portion, and is supported by the member 13, the latter being narrower than the member 13^a, as shown by Figure 2. If desired, however, the member 13^a may be omitted, the member 13 being of sufficient width to support all parts of the member 12, as shown by Figure 3. The member 13 surrounds a cen- 100

tral opening 15, and is provided with a plurality of integral clamping tongues 14, projecting outward from the opening and pressed downward upon the facing portion 12, to confine it in place.

The clutch above mentioned includes a plurality of flexible unstanding tongues 16, integral with the member 13, and projecting upward from the margin of the opening 15, and provided with outer hooks 17, and inner hooks 18, and a normally expanded split ring 19, engaged with said hooks, as shown by Figures 2 and 3. Figure 4 shows the relative positions of the tongues 14 and 16 when they are engaged with the facing portion 12 and split ring 19, said facing portion and ring being omitted from this figure. The ring is compressed and the tongues 16 are sprung slightly inward, when the clutch is forced into the core, and the effort of the ring to expand causes the clutch to frictionally engage the internal surface of the core. The frictional engagement permits the removal of the attachment from the cop, so that it may be engaged with another cop.

The member 13, tongues 14 and 16, and hooks 17 and 18 may be formed from the discoidal blank shown by Figure 5, portions of which are removed to form an opening 20, defining the margins of the tongues and portions of the margin of the opening 15, the opening being completed by the operation of bending the tongues, as shown by Figure 4. Margins of the inner hooks 18 are formed by annular slits 21, said hooks being offset inwardly from the tongues 16, as shown by Figure 4.

The invention may be embodied as shown by Figure 6, in which the head is composed of an annular compressible facing portion 22, and an annular rigid base portion 23.

The clutch is composed of a plurality of upstanding flexible fingers 24, integral with a sheet metal ring 25, bearing on the upper side of the facing portion 22, and a split ring 26, grasped by hooks 27 on the free ends of the fingers. The clutch is frictionally engaged with the internal surface of the core *a*, in the manner already described. The ring 25 is provided with integral tongues 28, which extend through the central opening of the head and are bent outward against the under surface of the base portion 23. The ring 25 and tongue 28 clamp the facing portion and base portion together.

The embodiment shown by Figures 7 and 8 includes an annular sheet metal head 30, adapted to bear on an end of the cop, and provided with a central opening. The clutch is formed by a plurality of upstanding flexible fingers 31, integral with the head and arranged to bear on the internal surface of the core, and a resilient split ring 32, the periphery of which bears on the

inner sides of the tongues 31, and is engaged therewith only by friction, and not positively, as in the other embodiments. The normal diameter of the ring is such that the ring may be forced into the opening of the head, and slightly contracted by contact with the tongues, the ring acting, by its effort to expand, to press the tongues 31 outward into frictional engagement with the internal surface of the core. The frictional engagement of the tongues with the core thus caused, is sufficient to maintain the attachment in operative engagement with the core, under all conditions of use, and to permit its separation from the core. The head 30, in this instance, has an annular marginal upstanding flange 33, surrounding the lower end of the cop.

It will now be seen that in each of the described embodiments of the invention, flexible tongues and a split ring constitute a clutch adapted to frictionally engage the internal surface of the core, the clutch being compressible by the core, and frictionally engaged with the internal surface thereof.

It will be seen that in the preferred embodiment shown by Figures 1 to 4, the tongues 16 having the spaced apart outer and inner hooks 17 and 18, are adapted to support a split ring 19, of considerable width, so that the clutch has a firmer engagement with the core *a* than when the split ring is relatively narrow and is supported only by the outer ends of the tongues as shown by Figure 6. Provision may be made for the employment of a still wider split ring, by forming the blank as shown by Figure 5^a the form and arrangement of the tongues 16 being such that the tongues are longer in proportion to the diameter of the central opening than is possible when the blank is formed as shown by Figure 5.

I claim:

1. For use with a thread cop which includes a tubular core and a thread body wound thereon, a guarding attachment comprising an annular head formed to bear on an end of the cop and provided with a central opening, and a clutch including a series of flexible tongues supported by the head and projecting upward from the margin of said opening, and a normally expanded split ring engaged with said tongues, the ring being contractible from its normal diameter, so that its effort to expand causes the clutch to frictionally engage the internal surface of the core.

2. For use with a thread cop which includes a tubular core and a thread body wound thereon, a guarding attachment comprising an annular head formed to bear on the end of the cop and provided with a central opening, and a clutch including a series of flexible tongues supported by the head and projecting upward from the margin of

said opening, the tongues being provided with ring-grasping means, and a normally expanded split ring grasped by said means, the ring being contractible from its normal 5 diameter, so that its effort to expand causes the clutch to frictionally engage the internal surface of the core.

3. For use with a thread cop which includes a tubular core and a thread body 10 wound thereon, a guarding attachment comprising an annular head formed to bear on the end of the cop and provided with a central opening, and a clutch including a series of flexible tongues supported by the 15 head and projecting upward from the margin of said opening, and a normally expanded split ring engaged with said tongues, the ring being contractible from its normal diameter, so that its effort to expand causes 20 the clutch to frictionally engage the internal surface of the core, the tongues being provided with opposed outer and inner hooks, respectively grasping the outer and inner edges of the ring.
- 25 4. For use with a thread cop which includes a tubular core and a thread body wound thereon, a guarding attachment comprising a head formed to bear on an end

of the cop, and provided with a central opening, the head including an annular facing portion of compressible material contacting with the cop, and an annular base portion supporting the facing portion and provided with a series of integral outwardly projecting clamping tongues confining the 30 facing portion, and with a series of upstanding flexible tongues having ring-grasping means, and a normally expanded split ring grasped by said means, the upstanding tongues and the ring constituting 35 a clutch projecting upward from the margin of the head opening, the ring being contractible from its normal diameter, so that its effort to expand causes the clutch to frictionally engage the internal surface of 40 the core.

5. A guarding attachment as specified by claim 4, the upstanding tongues alternating with the clamping tongues and having outer hooks grasping the outer edge of the split 45 ring, and inner hooks grasping the inner edge of said ring.

In testimony whereof I have affixed my signature.

ROBERT N. CORTHELL.
